UNITED STATES PATENT OFFICE.

ROSS VERNON CRAGGS, OF GAINSBOROUGH, ENGLAND, ASSIGNOR TO RICHARD HARVEY WRIGHT, OF DURHAM, NORTH CAROLINA.

FEED-REGULATOR.

1,054,509.

Specification of Letters Patent. Patented Feb. 25, 1913.

Application filed June 29, 1911. Serial No. 636,037.

To all whom it may concern:

Be it known that I, Ross VERNON CRAGGS, a citizen of the United States of America, residing in Gainsborough, England, and whose post-office address is Albion Works, Gainsborough, in the county of Lincoln, England, engineer, have invented a certain new and useful Feed-Regulator, of which the following is a specification.

10. This invention relates to hoppers or tanks for feeding granular and pulverulent materials in bulk to apparatus for weighing or filling and packing such materials into receptacles or for dealing with the materials 15 in other ways, and it consists in improvements having for their object to prevent the bridging or packing of the material within the hopper so as to insure a steady bulk flow to the apparatus co-operatively connected with the hopper. It has been previously proposed, for the purpose stated, to provide the hopper with a continuously revolving stirrer arranged either near its mouth or along the axis of the hopper and 20 in the latter case furnished with transverse blades carrying longitudinally disposed scrapers in close proximity to the walls of the hopper, but such devices have not proved as efficient as desired. It has been 25 proposed to support within the hopper a closed casing through which passes a stirrer rod; the projecting end portions of this rod carrying cross pins, which, as the rod is vertically reciprocated by means of a rotating crank, stir up the upper and lower portions of the material within the hopper, but 30 no movement is imparted to the central portion of the material.

Now this invention consists in an improved construction of agitating device which, while adapted to be reciprocated in an up and down direction, is fully exposed throughout its entire length to the material within the hopper, so that the said material 40 may be acted upon by the device from top to bottom so that it will, in the event of any bridging or arching of the material contained in the hopper, occurring, break up such arching which thereupon collapses and 45 falls.

The invention will be described with reference to the accompanying drawings, in which—

Figure 1 is a vertical section of a feeding hopper showing one form of the agitating

device for obviating the bridging or packing of material fed thereto; Fig. 2 is a side elevation of the hopper showing means for imparting a reciprocating motion to the device in Fig. 1; Fig. 3 is a part plan of the 60 hopper; Fig. 4 is a part elevation and part vertical section of a hopper showing another form of the agitating device, Fig. 5 is a part plan of the hopper of Fig. 3; Fig. 6 represents a vertical section on the 65 line 6—6 of Fig. 1.

The same letters are applied to the corresponding parts in the several figures.

The agitating device shown in Figs. 1-3 comprises a rocking shaft *a* suitably journaled in the opposite sides of the hopper *c* and carries near each of its ends within the hopper two oppositely extending arms *b*, from the arms depend movable panels which are pivoted at *b*¹ and consist of members *d*, 70 and a series of bars *e*, which as shown in Fig. 1 are preferably downwardly inclined toward the axis of the hopper, and slightly undercut as at *e*¹ in a manner to facilitate the downward compression of the material. 80 The lower ends of the members may be provided with rollers *f* or the like, adapted to engage the walls and thereby act as guides during the rocking or reciprocating movements imparted to the panels *d*. 85

Below the agitating members, about level with the outlet *c*¹ of the hopper, and above the mouth a stirrer *g* on a continuously revolving horizontal shaft *h* may also, if desired, be used in the customary manner. 90

Such an arrangement is very efficient if there be but one outlet from the hopper, but should there be more than one outlet, it has been found that arching of the material may occur at the bottom of the hopper between two or more outlets, and a steady bulk flow of the material will be interfered with. To obviate this, according to this invention, a transverse screw member or worm *i* is provided below the agitating panels and below the horizontal stirrer if one be employed, which worm, fitted to a shaft *j*, is operated so that it alternately turns first in one direction and then in the opposite direction. These alternate movements effectually break up any bridging of the materials that may momentarily arise between the outlets, *c*¹ of the hopper, or an outlet and the hopper wall. 105

The rocking of the shaft for actuating 110

the movable panels and the rotating of the worm or screw member in the two directions may be effected by means of a single reciprocating rod *k* suitably mounted exteriorly of the hopper, one extremity of which is provided with tappets or stops *k*¹ which may be adjustable and are adapted to engage and move in opposite directions one end of a lever *l* fixed at its other end to the 10 rocking shaft *a*. The other extremity of the rod *k* is provided with a rack *m* that meshes with a pinion *n* carried by the worm shaft *j*. The rod may be reciprocated by means of a link or bar *o* having one end 15 pivotally connected to the rod *k* while the other end is in co-operative engagement with a cam *p* driven from any source of power, for instance the power shaft, of the material weighing, filling or other apparatus. 20 As the rod is reciprocated it rocks the shaft and turns the worm alternately first in one direction and then in another.

In the case of a hopper having more than one outlet, there may either be a single agitating device or a series of such devices on the rocking shaft.

In Figs. 4-5 the movable agitating panel instead of being arranged alongside of the sides of the hopper as in Figs. 1-3, is arranged centrally within the hopper. It is shown provided with bars *e* and at its lower end is furnished with arms carrying rollers *f* which are adapted to contact with the walls of the hopper when the panel is in its 35 lowest position and thereby maintain it in a central position. This central movable panel may be operated in the same manner as has been described in respect to the side panels, and as it moves up and down it will 40 effectually break up the crown portion of any arching of the material that may arise and thereby cause the arch to fall in.

Having thus described the nature of my said invention and the best means I know of 45 carrying the same into practical effect, I claim:—

1. In apparatus for feeding powdery and granular materials, the combination of a feed hopper having an outlet toward the 50 bottom thereof, an agitating panel contained within the hopper and embodying a series of vertically spaced transversely extending bars, and means for reciprocating said panel in a direction toward and from 55 said outlet.

2. In apparatus for feeding powdery and granular materials, the combination of a feed hopper having an outlet, a pair of agitating panels arranged in opposed relation in the hopper and in co-operative relation 60 with opposed walls, and means for reciprocating said panels in directions toward and from said outlet.

3. In a hopper for feeding granular and pulverulent materials, a device for insuring 65 a steady bulk flow of material from the hopper, comprising in combination a rocking shaft supported by the hopper, arms fixed to the shaft within the hopper, a reciprocating agitating panel pivotally connected at one end to the arms, the panel carrying guiding members adapted to contact with the sides of the hopper and thereby by control the position of the panel, and means for rocking said shaft. 75

4. In a hopper for feeding granular and pulverulent materials, a device for insuring a steady bulk flow of material from the hopper, comprising in combination a rocking shaft supported by the hopper, arms 80 fixed to the shaft, a reciprocating movable panel pivotally carried by the arms within the hopper, means for rocking said shaft, a screw member disposed transversely above the outlet or outlets of the hopper and 85 adapted to be turned in two directions, and means adapted to rock the shaft and turn the screw member alternately in two directions.

5. In a hopper for feeding granular and 90 pulverulent materials, a device for insuring a steady bulk flow of material from the hopper, comprising in combination a rocking shaft supported by the hopper, arms fixed to the shaft, reciprocating agitating 95 panels, pivotally carried by the arms within the hopper, means for rocking said shaft, screw members disposed transversely each above the outlet or outlets of the hopper and adapted to be turned in two directions, 100 and means adapted to rock the shaft and turn the screw members alternately in two directions.

In testimony whereof I have signed my name to this specification in the presence 105 of two subscribing witnesses.

ROSS VERNON CRAGGS.
